TELEVISION SYSTEM

Rudolf Urtel, Berlin, Germany, assignor to Telefunken Gesellschaft für Drahtlose Telegraphie m. b. H., Berlin, Germany, a corporation of Germany

Application March 17, 1936, Serial No. 69,318
In Germany March 25, 1935

4 Claims. (Cl. 178—7.2)

This invention relates to television systems and in particular, to the synchronizing method for use with skip-line or interlacing television systems.

- 5 For the transmission of pictures in television it is known to use the so-called line skip method residing in that the lines 1, 2, 3 etc. of the picture to be transmitted, are sent out in two series, the first of which covering only the lines 1, 3, 5 etc. while the second one contains the lines 2, 4, 6 etc. and will be sent out only following the transmission of all lines of the first series. This known method may also be applied in such manner that the picture is divided into three or n -series of lines, whereby in case of three series of lines the first series covers the lines 1, 4, 7 etc., the second series the lines 2, 5, 8 etc. and the third one covers the lines 3, 6, 9 etc. In the case of n -series of lines, the first series of lines includes the lines 1, $n+1$, $2n+1$ etc. while the second series includes the lines 2, $n+2$, $2n+2$, etc. This method makes it possible at equal width of the frequency band required for the picture transmission, to multiply the scanning frequency 25 in the direction at right angle to, or almost at right angle, to the direction of the line, thereby considerably reducing the highly disturbing impression of flickering at the receiver. The method as described, requires a reproducing arrangement at the receiver in which the first line of each series of lines (seen in the direction at right angle or almost at right angle to the line direction) starts at another place of the reproducing screen. This is especially desirable if for instance a Braun tube is to be employed for reproducing the image. In this case, a deflection potential is required having a different starting point at each series of lines, and which is permitted to return to the same voltage value only 30 after the completion of n -series of lines. However, such deflection voltages to be produced require considerable means.

Accordingly, it is the object of my invention to provide a new and novel method of improving 35 synchronizing of television receiving systems in which skip-line or interlaced scanning is used.

Referring now to the drawing, in which

Fig. 1 shows schematically the simple skip-line scanning;

0 Fig. 2 shows schematically multiple skip-line scanning; and

Fig. 3 shows in box diagram my arrangement for improving the synchronizing of skip-line scanning; my invention will be described in detail.

But it is possible to overcome this disadvantage when resorting to a line skip method which may be designated as line skip method operating with line division. The functioning of this method will be elucidated with reference to Figure 1 of the drawing representing the relative position of two series of lines ($n=2$) on the receiving screen. For the sake of simplification in this Figure 1 an image consisting of only 9 lines is assumed whereby the first series includes the lines 1, 3, 5, 7 and the first half of the 9th line (these lines are indicated in Figure 1 by full lines), while the second series of lines consists of a half line which may be considered as the second half of the 9th line, but displaced relative to the first half by the entire height of the picture, and this second series furthermore includes the lines 2, 4, 6 and 8 (the lines of the second series are indicated in Figure 1 by dash lines). Following the transmission of the second series of lines i. e. after the completion of line 8 in Figure 1, the first series of lines will again be transmitted beginning at the left end of line 1. It can be readily seen that in this special line skip method, the scanning movement of the luminous spot in the vertical direction has to start always from the same initial point, since the starting point p_1 of the first series of lines and the starting point p_2 of the second line series are situated in the same height while furthermore the duration of each series of lines is the same.

This method may be also correspondingly applied in the case of three or more series of lines as will be readily understood from a study of Figure 2 in which the first line series is indicated in full lines, the second one in dash lines, and the third one in dot and dash lines.

However, in both types of the line skip method as described, a difficulty is encountered in avoiding the relative displacement of the two line series in the vertical direction; to such displacement the eye is extremely sensitive even if it amounts only to $\frac{1}{10}$ of the height of the line. There exists, however, a possibility for such displacement in view of the fact that the impulse of the line series increases but very slowly as to time in the receiver; this increase extending over several lines if as is ordinarily the case, the line series impulses are distinguished from the line impulses by its duration. Furthermore, in the last mentioned line skip method, it is to be borne in mind that (in the example according to Figure 1) the impulse which interrupts the 9th line and leads to the beginning of the second line series, follows the last line impulse at a distance equal to

the duration of a half line and during which the 9th line has been initiated, while the line series impulse beginning at the termination of the 8th line and through which the first line series will again be started, is displaced as to time from the line impulse of the 8th line by an amount equal to a total duration of the line. This fact is of importance since that circuit of the receiver which responds to the line series impulse behaves differently in accordance as to whether a line impulse appeared at a preceding half- or total duration of the line.

A suggestion to overcome this difficulty resides in providing an auxiliary generator oscillating during the last line of each line series, and which produces an impulse in the center of each line at $n=2$, and after $\frac{1}{3}$ and $\frac{2}{3}$ of the duration of the line at $n=3$, said impulse serving to simulate for the circuit to respond to the line series impulse, identical conditions at the termination of each line series.

Furthermore, before each line series impulse, care can be taken by means of a readiness impulse, that the line series impulse always finds that circuit in the same state which is to be excited by said line series impulse.

Such auxiliary measures are dispensed with in accordance with the invention, in that the line impulse and the line series impulse are transmitted to the receiver on separate transmission channels. It is to be preferred that the line series impulse having a frequency of 5000 in case of a picture of 200 lines and 25 picture transmissions per second, be sent out on the sound transmission channel i. e. over the transmission line or carrier wave on which the sounds accompanying the picture reproduction are transmitted, while the line series impulse having a frequency of 50 at $n=2$ and 25 pictures per second, be transmitted on the picture transmission channel, or on the picture transmission carrier wave as shown schematically in the block diagram of Fig. 3. In the receiver, the arrangement serving for the release of the line deflection and that which releases the line series deflection are placed at separate transmission channels, namely according to the above-mentioned suggestion, the line deflection arrangement to be placed at the sound transmission channel, the line series deviation arrangement at the picture transmission channel. In a circuit arrangement constructed in accordance with the invention, for transmitter and receiver, the aforementioned auxiliary means are dispensed with while avoiding at the same time with absolute

assurance, a relative displacement of the two line series.

What I claim is:

1. The method of transmitting television signals which includes the steps of transmitting over a first channel electrical signals representative of an optical image to be transmitted, transmitting over a second channel electrical signals representative of accompanying sound energy related to said optical image, transmitting over 10 said first channel electrical signals related to the synchronous reproduction of said optical image, and transmitting over said second channel other electrical signals also related to the synchronous reproductions of said optical image, said other 15 electrical signals having a different character than said third named electrical signals related to the synchronous reproduction.

2. In a television system wherein is provided two related transmitters, the method of transmitting pictures which includes the steps of actuating one of said transmitters both by signals representative of the picture to be transmitted and by synchronizing signals of a predetermined character, and actuating the other of said two 25 transmitters both by signals representative of accompanying sound energy related to said picture and by synchronizing signals of a different character from those of said first named synchronizing signals.

3. In a television system wherein is provided two related transmitters, the method of transmitting pictures which includes the steps of actuating one of said transmitters both by signals representative of the picture to be transmitted 35 and by synchronizing signals of a predetermined frequency, and actuating the other of said two transmitters both by signals representative of accompanying sound energy related to said picture and by synchronizing signals of a different frequency from the predetermined frequency of said first named synchronizing signals.

4. In a television system wherein is provided two related transmitters, the method of transmitting pictures which includes the steps of actuating one of said transmitters both by signals representative of the picture to be transmitted 45 and by frame synchronizing signals, and actuating the other of said two transmitters both by signals representative of accompanying sound energy 50 related to said picture and by line synchronizing signals.

RUDOLF URTEL.
